REFRIGERATION EXPANSION VALVE

Earnest J. Dillman, Detroit, Mich., assignor to
 Detroit Lubricator Company, Detroit, Mich., a
 corporation of Michigan

Application July 17, 1944, Serial No. 545,372

9 Claims. (CL. 137—153)

1

This invention relates to new and useful improvements in refrigerating apparatus and more particularly to expansion valves for controlling the flow of refrigerant medium to an evaporator.

An object of the invention is to provide a valve of simple and compact form which can be readily produced in large quantities.

Another object is to provide a novel operating connection for transmitting the movement of the pressure responsive member to the valve member.

Another object is to provide novel supporting and securing means for the motion transmitting member.

The invention consists in the improved construction and combination of parts to be more fully described hereinafter and the novelty of which will be particularly pointed out and distinctly claimed.

In the accompanying drawing to be taken as a part of this specification, there are fully and clearly illustrated several preferred embodiments of the invention, in which drawings:

Figure 1 is a view in vertical central section of a cast body type valve shown operatively connected in a diagrammatic refrigerating system;

Fig. 2 is an enlarged detail view showing the interconnection of the valve operating member and pressure responsive diaphragm;

Fig. 3 is a view in vertical central section of another form of valve, constructed in large part of sheet metal;

Fig. 4 is a plan view looking at the top of Fig. 3, and

Fig. 5 is a view in vertical central section of a valve similar to that of Fig. 1, but provided with an external equalizer connection.

Referring to the drawings by characters of reference in Figs. 1 and 2, 1 designates generally a hollow body member or casing of cup-like form having a substantially cylindrical pressure chamber 2. The side wall of the casing at its open side or end has an annular internal recess providing an outward facing shoulder 3. Seating on the shoulder 3 and substantially fitting the shoulder recess is the marginal portion of a pressure responsive resilient metal diaphragm 4, preferably a substantially flat plate or member of beryllium copper which seals the open cas-

2

ing end. Also supported on the shoulder 3 and substantially fitting the shoulder recess there is a reinforcing and supporting means including a reinforcing spider 5 on the pressure chamber side of the diaphragm and an abutment and supporting plate 6*. The diaphragm has a marginal flange 6 which projects upward or outward from the diaphragm edge and fits the side wall of the annular recess. The diaphragm 4 and spider 5 are tightly held and clamped to the shoulder 3 by a cover or closure member 7 which is bent or formed to have a marginal bead 8 which overlies the shoulder 3 and which provides a central circular recess 9 cooperable with the diaphragm 4 to provide a fluid pressure chamber. The cover member 7 has a marginal surrounding flange 10 which seats laterally against the inner face of the diaphragm flange 6 which terminates short of the top edges of the casing side wall and the flange 10 to provide an annular sealing material receiving channel. Sealing material 11, such as solder, fills this channel and hermetically seals the cover member flange 10 to the casing side wall and also hermetically seals the diaphragm flange 6 to the cover member flange 10 and to the casing side wall. Opening into the recess or chamber 9 through a central opening in the cover member 7 and hermetically sealed therein, there is one end of a capillary tube 12 having its other end communicating and hermetically sealed to a feeler bulb or member 13. The chamber 9, tube 12, and bulb 13 are evacuated of air and filled with a temperature responsive liquid so that the diaphragm 4 will be moved or respond to the temperature of the bulb 13.

The bottom or end wall 14 of the casing 1 opposite the diaphragm 4 has a centrally positioned conduit member with projecting end portions 15, 16 extending from the opposite wall faces and providing an inlet passage or conduit 17 leading through the wall 14 into the chamber 2 concentric with the diaphragm 4. The passage 17 is of enlarged diameter intermediate its ends to provide an outward facing annular seat or shoulder 18. Press fitted into this enlarged passage portion and limited against inward movement by seating against the shoulder 18, there is a tubular valve seat member 19, preferably of stainless steel tubing. Outward

of the seat member receiving bore or passage portion, the passageway or bore is enlarged to provide with the side wall of the member 18 a strainer receiving annular channel or recess 20 which flares within the end portion 16 into a still further enlarged diameter passage or bore portion 21 which provides a valve and strainer chamber.

The conduit member inner end portion 15 extends substantially to the diaphragm 4 to provide a stop to limit inward diaphragm movement and is externally screw-threaded to receive an adjustable spring supporting plate member 22. Supported on the member 22 by a friction washer 23, there is a helical coil spring 24 which surrounds the end portion 15 and which has its upper end seating against the reinforcing plate member 5 which abuts and is held to the central portion of the spider 5 so that the spring opposes inward movement of the diaphragm 4. The reinforcing plate or member 5^a and the spider 5, are rigidly secured and permanently joined together by spot welding at a plurality of points, as indicated at 26, Fig. 2. The plate 5^a has a central conical recess or socket 27 facing the diaphragm 4 and has an aperture 28 therethrough opening into the recess 27 substantially concentric with the bore of the valve seat member 19. Positioned in the recess 27 and seating against the wall thereof, there is the head 29 of a force transmitting pull wire 30 which extends through the aperture 28. The head 29 also abuts the diaphragm spider 5 so that there is no lost-motion between the wire 30 and the diaphragm. The wire 30 is a laterally reflexible resilient member, preferably a beryllium copper, and for domestic valve sizes may have a diameter of say .030". The wire 30 extends loosely through the conduit member bore and the bore of the valve seat member 19 to provide an annular flow passage and also through the bore of an elongated tubular valve member 31 which is sleeved on the valve chamber end of the wire 30 and which is preferably of stainless steel tubing. The wire 30 fits the bore of the valve member 31 and is sealed and secured in the bore by a solder connection 32 at the opposite or outer end of the valve member from the valve seat member. The valve member 31 has a conical or tapered valve end portion concentric with its bore and cooperable with a valve seat formed by the inlet end of the valve seat member.

Surrounding the valve member 31 and the valve seat member 19 and seating on the bottom of the channel 20 there is an end portion of a cylindrical strainer 33 having a closed outer end and carried by a U-shaped spring member 34 having its ends frictionally engaging the internal side walls of a tube receiving fitting 35. The tapered end of the fitting 35 receives the flared end portion of the refrigerant liquid line or tube 36, the flared tube end being clamped and sealed to the fitting 35 by the usual clamping nut 37 which is screw-threaded on the conduit end portion 16.

The valve is adjustable by regulation of the force of the spring 24 and this is accomplished by a pinion 38 in mesh with teeth on the periphery of the spring supporting plate 22. The pinion 38 is carried by a shaft 39 journaled in the walls of the casing 1 and having an end portion 40 projecting externally thereof. Clearance for the shaft 39 is sealed against leakage by packing material 41 and the shaft end 40 is enclosed by a cover member or cap 42.

The liquid line 36 leads from and is connected to a refrigerant receiver 43 which is fed with refrigerant from a condenser 44 connected by a conduit 45 to the outlet of a motor driven compressor 46. The diaphragm pressure chamber 2 has an outlet 47 through the side wall of the casing 1 and connected by a conduit 48 to the inlet of an evaporator 49. The thermostatic bulb 13 is clamped adjacent the outlet of the evaporator 49 to the refrigerant suction line 50 which leads from the evaporator to the inlet of the compressor 46.

The operation of this valve of Fig. 1 is as follows: The force of the spring 24 is adjusted by the pinion 38 to determine the suction pressure and therefore the temperature of the refrigerant medium in the evaporator 49 and in the diaphragm chamber 2 at which the valve member 31 will be moved to open position. When the compressor 46 is now started by the usual automatic means, not shown, responsive to desired high suction line pressure or high evaporator temperature, the back pressure of the refrigerant medium in the chamber 2 will be reduced, and when this back pressure, plus the force exerted by the spring 24, becomes less than the force exerted by the thermostatic power element, the diaphragm member 4 will be moved downward by the pressure of the temperature responsive liquid in the chamber 2 and move the valve member 31 to open position. The forces acting against opposite faces of the diaphragm member 4 will now throttle the valve member 31 to regulate the flow of refrigerant medium through the valve seat member 19 into the chamber 2 and thence through the conduit 48 to the evaporator 49. When the evaporator 49 becomes refrigerated throughout its length, which depends upon the superheat setting of the valve, as is well understood in the art, then the temperature of the bulb element 13 will decrease, thereby permitting the valve member 31 to be pulled to closed position by the valve operating wire 30. However, in normal operation, while the compressor 46 is in operation the valve member 31 will not be seated but will be throttled to bleed sufficient refrigerant medium to the evaporator 49 to maintain the evaporator refrigerated throughout its length. When the suction pressure is reduced to the desired low point or the temperature of the evaporator or of the space cooled thereby reaches the desired low temperature, then the automatic control means, not shown, will function in the usual manner to stop operation of the compressor. The back pressure of the refrigerant medium will therefore increase and, together with the force of the spring 24, will overcome the force of the power element and move the valve member 31 to closed position. The force transmitting wire 30 by its flexibility, its head end being centered and fixed by the spider 5, permits the valve member 31 to have some lateral movement for manufacturing tolerance so that it will be accurately seated against the valve seat member 19 and will not cause uneven wear of the valve seat, resulting in leakage of refrigerant medium. Excessive back pressure in the chamber 2 will not jam the valve member against its seat, since the diaphragm is free to move outward away from the spider 5.

Referring to Figs. 3 and 4, the valve body or casing 101 is a stamped sheet metal cup-like member, preferably of brass, having its bottom or end wall 102 provided with radially extending reinforcing ribs 103. The open side or end of

the casing 101 is closed by a resilient sheet metal diaphragm comprising a diaphragm member 104, preferably of beryllium copper, and a reinforcing spider 105 which are clamped together at their marginal edges which seat on the open end of the casing side wall. The diaphragm member 104 has a marginal flange 106 which sleeves over and laterally fits the casing side wall and which also fits and centers the spider 105. Cooperable with and overlying the diaphragm there is a cover member 107 having a central circular recess 108 which cooperates with the diaphragm member 104 to provide a thermostatic power element pressure chamber. The marginal portion of the cover member 107 clamps the diaphragm to the casing side wall and has a peripheral flange 109 which fits and is sleeved over the diaphragm flange 106. The flange 109 extends beyond the flange 106 to provide an annular channel to receive a sealing material 110, such as solder, which hermetically seals and joins the cover member flange 109 to the casing side wall and simultaneously hermetically seals and joins the diaphragm to the flange 109 and to the casing side wall, thereby sealing the chamber 108 and also the pressure chamber 111 within the casing 101. Opening centrally through the cover member 107 into the chamber 108 there is a capillary tube 112 hermetically sealed in the cover member. A bulb element 113 is hermetically sealed and secured to the free end of the tube 112 and, together with the chamber 108, provides a thermostatic power element which is evacuated of air and filled with a temperature responsive liquid.

The casing bottom or end wall 102 has a central aperture therethrough in which there is sealed a conduit member 114 having an inner end portion 115 which extends substantially to the diaphragm member 104 to provide a stop to limit inward movement of the diaphragm. The end portion 115 has a centrally apertured end wall and a lateral outlet 116 opening from the conduit member inlet passage or bore 117 into the chamber 111 to assure free flow from the conduit member. The side wall of the casing 101 is provided with an outlet fitting 118 for connection to the evaporator inlet pipe or conduit, such as 48 of Fig. 1. Adjustably screw-threaded on the portion 115 there is a spring supporting and adjusting member 119 having a toothed or serrated rim 120 accessible for spring adjustment through the outlet 118. Seating against the member 119 is one end of a helical coil compression spring 121 which surrounds the end portion 115 and which has its other end seating against a reinforcing plate member 122 which is similar to the plate member 5^a and which is secured to the spider, preferably by welding as indicated in Fig. 2.

The bore or inlet passage 117 is enlarged, as at 123, to receive a tubular valve seat member 124, preferably made from a piece of stainless steel tubing. The seat member 124 is press fitted into the enlarged portion 123 and seats against the annular step or shoulder formed at the inner end of the enlarged bore portion. The valve seat member 124 is received within the outer end portion 125 of the conduit member 114. This end portion 125 has an enlarged internal diameter to provide a valve chamber 126 into which the valve seat member 124 projects. Within the chamber 126 there is a tubular valve member 127, preferably made from a piece of stainless steel tubing, and having concentric with

its bore, a conical or tapered valve portion co-operable with the valve seat formed by the outer end of the valve seat member 124. The valve member 127 is connected to the diaphragm member 104 by a laterally flexible resilient and force transmitting wire 128 which extends loosely through the bore of the valve seat member 124, and which is preferably of beryllium copper. The wire 128 fits and extends through the bore of the valve member 127 and is hermetically sealed to the valve member by solder, for example, as at 129. The other end of the wire 128 extends loosely through the end wall aperture of conduit portion 115 and through a central opening in the reinforcing member 122 which has a conical recess facing the diaphragm member 104 similar to the reinforcing member 5^a. The end of the wire 128 within the reinforcing recess is provided with a conical head which seats and is held against the recess wall by the diaphragm spider 105, in the same manner as the head 29 of Fig. 4. The conduit member valve chamber portion 125 is provided with an inlet fitting 130 for connection to a refrigerant medium liquid line such as the conduit 36 of Fig. 1. The fitting 130 provides a strainer chamber for an inlet strainer 131, preferably of cone form having its base edge seated on the end of the conduit portion 125. The operation of the valve of Figs. 3 and 4 will be apparent from the above description of the valve of Fig. 1.

Referring to the expansion valve of Fig. 5, it is substantially like that of Fig. 1 except that it is constructed for operation with an external equalizer. The diaphragm refrigerant back pressure chamber 150, corresponding to the chamber 2 of Fig. 1, is separated and closed off from the flow of refrigerant medium passing through the valve. This is accomplished by closing the inner end of the conduit member by packing, as at 151, so that leakage around the pull wire 30 will be prevented. The packing 151 is held under compression by a helical coil spring 152 which surrounds the wire 30 and seats against the annular shoulder formed by the outlet end of the valve seat member 19. The chamber 150 has an equalizer connection or outlet 153 through its side wall for connection by a pipe or conduit (not shown) to the refrigerant suction line adjacent the evaporator outlet, as is well understood in the art. The refrigerant outlet from the valve casing and the conduit 17 is through a port 154 intermediate the valve seat member and the packing material 151. The port 154 is connected at the outlet fitting 155 to the refrigerant liquid line which leads to the evaporator inlet. The operation of this valve will be apparent from the description of the valve of Fig. 1, the only difference being that the diaphragm 4 will respond to refrigerant pressure at the evaporator outlet, as distinguished from the pressure at the evaporator inlet as in the valve of Fig. 1.

What is claimed and is desired to be secured by Letters Patent of the United States is:

65 1. In a refrigeration expansion valve, a casing having an annular seat and having a passageway therethrough concentric with said seat, a tubular valve seat member in said passageway, a diaphragm supported at its periphery on said seat and forming an internal wall of said casing, a flexible reinforcing spider resting at its periphery on said seat and supporting said diaphragm member against inward valve opening movement, an abutment plate having a recess facing said spider and having an aperture therethrough opening

into said recess, said aperture and recess being concentric with said seat member, a tubular valve member in said passageway on the opposite side of said seat member from said diaphragm, said valve member having an end portion engageable with said seat member, a laterally flexible resilient member extending loosely through the bore of said valve seat member from said diaphragm and fitting the bore of said valve member, said flexible member extending through said aperture and having a head laterally located by the wall of said recess, means permanently joining said spider and said plate together to provide a unitary structure holding said head in said recess and concentric with said valve seat member, said diaphragm being free to move away from said spider, a spring acting against said plate and tending to hold said valve member against said seat member, and means sealing said flexible member in said valve member bore.

2. A refrigeration expansion valve comprising a hollow casing having a wall opening and a wall opposite said opening, the side wall of said casing having an outlet, conduit means extending transverse to said wall and having end portions projecting from the opposite faces of said wall, a pressure responsive member sealing said opening, one of said end portions extending substantially to said responsive member to limit inward movement of said responsive member, the other of said conduit means end portions having a valve seat therein, a valve member in said other end portion and cooperable with said seat, reinforcing means in said casing and supporting said responsive member, a spring surrounding said one end portion and seating against said reinforcing means to oppose inward movement of said responsive member, and a force transmitting member longitudinally reciprocal in said conduit member and connecting said valve member to said reinforcing means.

3. In a refrigeration expansion valve, a hollow casing having a wall opening and a wall opposite said opening, conduit means extending transverse to said wall and having alined end portions projecting from the opposite faces of said wall, a pressure responsive member sealing said opening, one of said end portions being radially spaced throughout its length from the side wall of said casing and having its end serving as a stop for said responsive member, the other of said end portions having a valve seat therein external of said casing, a valve member in said other end portion and having a tapered valve portion cooperable with said seat, said valve member having a longitudinal aperture therethrough concentric with said valve portion, reinforcing means engaging the side wall of said casing and engaging said responsive member, a spring supporting member adjustably screw-threaded on said one portion, a spring surrounding said one end portion and seating on said supporting member and against said reinforcing means to oppose inward movement of said responsive member, said reinforcing means including a plate having a recess facing said responsive member and having an aperture therethrough opening into said recess, a laterally flexible resilient wire longitudinally reciprocal in the bore of said conduit means and extending through said apertures, means sealing said wire in said valve member aperture, and a head portion on said wire within said recess for pulling said valve member against said seat.

4. A refrigeration expansion valve comprising a cup-shaped casing forming a chamber having

a side wall outlet and having an end wall, means forming an open-ended conduit extending transverse to and centrally of said wall and having end portions projecting from opposite faces of said wall, a diaphragm sealing the open side of said chamber, reinforcing means carried by said casing and supporting said diaphragm and including a spider and an abutment plate welded together, the inner end portion of said conduit forming means being threaded and extending adjacent to said diaphragm to limit diaphragm inward movement, a tubular valve seat member in said conduit-forming means, a tubular valve member having its bore alined with the bore of said seat member and controlling flow to said chamber, said plate having a recess alined with said seat member bore and having an aperture therethrough opening into said recess, an abutment member adjustably screw-threaded on said inner end portion, a helical coil spring surrounding said inner end portion and held under compression between said abutment member and said plate, a flexible resilient wire fitting and sealed in the bore of said valve member and extending loosely through said seat member bore and said conduit-forming means and extending through said plate aperture into said recess, and a head on said wire within said recess for transmitting the force of said spring to said valve member.

5. A refrigeration expansion valve comprising a hollow metal casing having a cylindrical pressure chamber with a side wall outlet and with an end wall and an open end, said chamber having an enlarged diameter at said open end to provide an outward facing shoulder, resilient metal diaphragm seating on said shoulder and having a peripheral flange fitting said enlarged diameter, a rigid closure member holding said diaphragm against said shoulder, sealing material joining said closure member to said casing and joining said flange to said casing and to said closure member, conduit-forming means integral with said end wall and having alined end portions projecting from the opposite faces of said end wall, one of said end portions extending into said chamber substantially to the face of said diaphragm and being externally screw-threaded, an adjustment disc screw-threaded on said one end portion, a reinforcing means abutting said diaphragm and having a disc with a central socket facing said diaphragm and alined with the bore of said conduit member, a helical coil spring surrounding said one end portion and held under compression between said discs to resist inward movement of said diaphragm, the other conduit means end portion being internally enlarged to provide a valve chamber, a tubular valve seat means intermediate the ends of and sealed in said conduit member bore and extending into said valve chamber, an elongated tubular valve member in said valve chamber and having a tapered valve portion cooperable with said seat member, a laterally flexible wire laterally movable and reciprocal in said conduit means bore and having one end portion fitting in and extending through the bore of said valve member, means sealing and securing said wire to said valve member at its opposite end from said tapered valve portion, said reinforcing disc having an aperture therethrough into said socket, said wire extending through said disc aperture into said socket, a head on the end of said wire within said socket and seating against the wall of said socket and transmitting the force of said spring to said valve member, and means

holding said socket alined with the bore of said valve seat member.

6. A refrigeration expansion valve comprising a cup-shaped sheet metal casing having an aperture through its end wall, a tubular conduit member extending through and sealed in said aperture and projecting centrally from opposite sides of said wall, a metal diaphragm closing the open side of said casing and having a peripheral flange fitting the external side wall of said casing, a rigid closure member seating on the periphery of said diaphragm, a marginal flange on said closure member fitting said diaphragm flange and extending therebeyond to provide with the casing side wall a sealing channel, sealing material in said channel and sealing said marginal flange to said casing and said diaphragm flange to said marginal flange and to said casing, the side wall of said casing having an outlet, the bore of said conduit member being transversely enlarged outward of said casing end wall to provide a valve chamber, a tubular valve seat member in and intermediate the ends of said bore and having an end portion projecting into said valve chamber, a reinforcing spider seating on and secured against the rim of said casing by said diaphragm, a reinforcing plate member in said casing and carried by and fixed centrally to said spider and having a central recess facing said spider, an adjustable abutment member screw-threaded on and surrounding said conduit member within said casing, a helical coil spring held under compression between said reinforcing member and said abutment member and resisting inward movement of said diaphragm, said reinforcing member having an aperture therethrough alined with said conduit member bore and opening into said recess, a laterally flexible pull wire in said valve chamber and extending through said bore and said plate aperture into said recess, a head on the end of said wire in said recess and heating against said spider and the wall of recess, said spider locating said recess and the head end of said wire substantially concentric with said valve seat member, a tubular valve member sleeved on and fitting said wire in said valve chamber and having at its inner end a conical valve portion cooperable with said seat member, and means sealing said wire in and to the outer end of the valve member bore.

7. A refrigeration expansion valve comprising a cup-shaped casing forming a chamber having an equalizer connection and having an end wall, an open-ended conduit member extending transverse to and centrally of said wall and having end portions projecting from opposite faces of said wall, a diaphragm sealing the open side of said chamber, reinforcing means carried by said casing and supporting said diaphragm and including a spider and an abutment plate welded together, the inner end portion of said conduit member being threaded and extending adjacent to said diaphragm to limit diaphragm inward movement, a tubular valve seat member in said conduit member, a tubular valve member having its bore alined with the bore of said seat member, said plate having a recess alined with said seat member bore and having an aperture therethrough opening into said recess, an abutment member adjustably screw-threaded on said inner end portion, a helical coil spring surrounding said inner end portion and held under compression between said abutment member and said plate, a flexible resilient wire fitting and sealed

in the bore of said valve member and extending loosely through said seat member bore and said conduit member and extending through said plate aperture into said recess, a head on said wire within said recess for transmitting the force of said spring to said valve member, packing material sealing the inner end of the bore of said conduit member around said wire, and a helical coil spring in said conduit member and compressing said packing material, the outer end portion of said conduit member having an outlet port leading from said conduit member bore on the outlet side of said seat member.

8. In a refrigeration expansion valve, a casing having a substantially cylindrical pressure chamber with a bottom wall and an open end opposite said wall, said casing having an annular shoulder at its open end, a flexible resilient spider seating on said shoulder, a diaphragm seating on said spider and having its marginal portion overlying said shoulder, means securing and sealing said diaphragm to said casing, a tubular projection extending from said wall concentric with and terminating adjacent said diaphragm to limit inward movement of said diaphragm, a spring supporting disc screw-threaded on said projection and having peripheral teeth, a helical spring surrounding said projection and seating on said supporting member and against said diaphragm, a pinion journaled in said casing and meshing with said teeth to adjust said supporting disc, said casing having an aperture alined with said pinion, a shaft extending from said pinion and projecting through said aperture, means sealing said aperture, a tubular extension projecting from said bottom wall externally of said casing and alined and communicating with said tubular projection, a valve seat member within said tubular extension, a valve member cooperable with said seat member, and an operating member extending through said projection and said extension and operatively connecting said diaphragm to said valve member.

9. In a refrigeration expansion valve, a casing having a substantially cylindrical pressure chamber with a bottom wall and an open end opposite said wall, said casing having an annular shoulder at its open end, a flexible resilient spider seating on said shoulder, a diaphragm seating on said spider and having its marginal portion overlying said shoulder, means securing and sealing said diaphragm to said casing, a tubular projection extending from said wall concentric with and terminating adjacent said diaphragm to limit inward movement of said diaphragm, a spring supporting disc screw-threaded on said projection and having peripheral teeth, said disc being operable upon rotation to have a range of movement longitudinally of said projection, a helical spring surrounding said projection and seating on said supporting member and against said diaphragm, a pinion journaled in said casing and meshing with said teeth to adjust said supporting disc, said disc being operable upon said longitudinal movement to move longitudinally of said pinion, the combined lengths of gear teeth on said pinion and said disc being at least as great as said range of longitudinal movement, said casing having an aperture alined with said pinion, a shaft extending from said pinion and projecting through said aperture, means sealing said aperture, a tubular extension projecting from said bottom wall externally of said casing and alined and communicating with said tubular projection, a valve seat member within said tubular extension, a valve

11

member cooperable with said seat member, and an operating member extending through said projection and said extension and operatively connecting said diaphragm to said valve member.
